UNITED STATES PATENT OFFICE

125,989

DESIGN FOR A DRESS OR SIMILAR ARTICLE

Herman Beispel, New York, N. Y.

Application December 21, 1940, Serial No. 97,529

Term of patent 3½ years

● *To all whom it may concern:*

Be it known that I, Herman Beispel, a citizen of the United States, residing in the city, county, and State of New York, have invented a new, original, and ornamental Design for a Dress or Similar Article, of which the following is a specification, reference being had to the accompanying drawing, forming part thereof.

Fig. 1 is a front view of a dress showing my design;

Fig. 2 is a rear view of the dress shown in Fig. 1;

Fig. 3 is an enlarged fragmentary view of the

dress shown in Fig. 1, illustrating one of the pockets in detail.

The characteristic feature of my design resides in the combination on the dress disclosed of the specific embroidered pockets on the lower front blouse portion, in association with the harmonizing embroidery about the neckline, and the pleated skirt, all as shown.

I claim:

The ornamental design for a dress or similar article, as shown and described.

HERMAN BEISPEL.
